STOVE DOOR AND WINDOW UNIT

Herbert E. Mills, Detroit, Mich.

Application October 20, 1948, Serial No. 55,609

2 Claims. (Cl. 126—200)

1

This invention relates to stove doors and window units.

A principal object of the invention is to provide a new and improved stove door and window unit arrangement.

Another object of this invention is to provide a double glazed window suitable for use in stove doors, so sealed that vapors from the oven can not enter between the glass, thereby insuring continued clear visibility through the glass.

Another object of the invention is to provide a new and improved form of double glazed window unit suitable for use in a door such as a stove door.

Another object of the invention is to provide a new and improved double glazed window unit which facilitates the assembly thereof into a door structure.

Other and further objects of the invention will be apparent by reference to the accompanying drawings of which there are two sheets, which, by way of illustration, show preferred embodiments and the principles thereof and what I now consider to be the best mode in which I have contemplated applying these principles. Other embodiments of the invention embodying the same or equivalent principles may be used and structural changes may be made as desired by those skilled in the art without departing from the present invention and the purview of the appended claims.

In the drawings:

Fig. 1 is a perspective view of a stove door embodying the invention;

Fig. 2 is an exploded perspective view of the several parts comprising the window unit;

Fig. 3 is a partial perspective view of the assembled window unit showing the method of clamping the several parts comprising the window unit together;

Fig. 4 is an elevation view of the back of an assembled stove door and window unit;

Fig. 5 is a side elevation view of the door;

Fig. 6 is a sectional view of the assembled door and window unit taken along line 6—6 of Fig. 4;

Fig. 7 is a partial sectional view showing a possible method of assembling the window unit;

Fig. 8 is a partial sectional view showing a modified form of the window unit; and

Fig. 9 is a view similar to Fig. 8 showing another modification of the window unit.

A stove door and window unit of the type described herein may comprise a front door panel 10, a back door panel 12, and a handle 14. Screws 16 are employed for securing the panels 10 and

2

12 together. The panels 10 and 12 have aligned openings 18 formed therein, and an inwardly turned flange 20 on each of the panels 10 and 12 surrounds the openings 18.

5 A window unit indicated generally at 22 is comprised of two tempered glass panels 24, a continuous channel-shaped spacing member 26, continuous rims 28, and channel-shaped clamping members 30. The spacing member 26 and rims 28 are made of very thin-gauged resilient stainless steel and have the same overall dimensions as the glass panels 24. The continuous rims 28 and spacing member 26 may be made of a strip of such material with the ends thereof suitably attached as at 32. The two opposing sides 34 of the spacing member 26 are flat but outwardly biased and arranged to engage the sides of the glass panels 24 to form a seal between the glass panels 24. The rims 28 have flat portions 36 which lie flat against the surface of the glass panel remote from the spacing member 26. The inner walls of the parallel sides of the channel-shaped clamping or retaining member 30 bear on the flat portion of the rims 28, thereby completely enclosing the various members of the window unit around their outside edges. The member 30 may be made of two L-shaped pieces, as shown in Fig. 2, and each may have a flange 38 with a hole 40 therein on one end thereof. Holes 42 are provided in the other ends of members 30 and each arranged to be in alignment with the hole 40 of the other clamping member when the unit is assembled. Screws 44 may secure the two sections of the clamping member 30 together. The parallel sides of the clamping member 30 may be provided with slits 45 between the corners and the inside edge of said parallel sides, as shown in Fig. 2, thereby permitting a slight distortion of the adjacent sides of each piece to facilitate the assembly of the unit.

The clamping members 30 may, if desired, be made of one continuous channel-shaped strip having a flange 38 and hole 40 therein on one end of said strip, and a hole 42 on the other end of said strip for securing the free ends of clamping member 30 together. In such a case, additional slits 45 could be provided in the parallel sides of the channel member 30 as desired.

The assembled window unit 22 is adapted to fit the openings 18 of the door panels 10 and 12. Flanges 46 on rims 28 are arranged to fit against the inwardly extending flanges 20 of the door panels 10 and 12, thereby locating the window unit with respect to the openings 18. The ends 55 of the inwardly extending flanges 20 bear on the

parallel sides of the clamping member 30, as shown in Fig. 6, thereby preventing movement of the unit within the door panels and also preventing the escape of heat from the interior of the oven.

Clamping means 48 may be provided on one of the panels, as shown in Fig. 6, so as to prevent any possible shifting of the window unit within the door. In the clamping device shown in Fig. 6, a bracket 50 is secured to door panel 12 adjacent each corner of the window unit. A clamp 52 is detachably secured to the bracket 50 by a screw 54, and bears against the window unit 22 thereby securing the same to the door panel 12 when the screw 54 is tightened. The clamps 52 and brackets 50 may be used for accurately locating the window unit within the openings 18 if desired, in which case the rims 28 could be dispensed with. The clamps 48 may be dispensed with if so desired.

The flanges 46 of the rims 28 will provide a very accurate alignment between the window-unit 22 and the flanges 20 of the door panel openings 18, thereby preventing any lateral movement of said window unit, and the ends of the flanges 20 will engage the channel-shaped clamping member 30 tightly enough to prevent any "in-and-out" movement of the window unit.

In the method of assembling the window unit shown in Fig. 7, the channel-shaped spacing member 26 has its opposing sides disposed outwardly away from each other before the assembly of the unit. The spacing member 26 is then placed between the glass panels 24 and the rims 28 are placed on the glass panels 24. Pressure exerted on the outside surfaces of the glass will press the diverging sides of channel 26 toward each other until the clamping member 30 can be secured around the edges of the several parts of the unit. Spacing member 26 is made of a thin-gauged resilient material so as to press tightly against glass panels 24, thereby insuring a good seal between the glass panels. The spacer 26 will also then tend to bias the glass panels away from each other thereby creating a further seal between the clamping member 30 and the rims 28.

In the modification shown in Fig. 8, a gasket 56 of sealing material is provided between the glass panels 24 and around the spacing member 26.

In the modification shown in Fig. 9, a continuous channel-shaped gasket 58 of sealing material is arranged around the edges of the glass panels 24 and seats on the outside surfaces of the glass panels. The rims 28 seat on the gasket 58. The gaskets 56 or 58 may be used so as to provide a more efficient, air-tight seal between the glass panels.

While I have illustrated and described preferred embodiments of my invention, it is understood that these are capable of modification, and

I therefore do not wish to be limited to the precise details set forth, but desire to avail myself of such changes and alterations as fall within the purview of the following claims.

I claim:

1. A window unit for use in a stove door having spaced front and back door panels each having a window opening in alignment with the opening in the other and each of said door panels having an inwardly extending flange around the edge of the opening therein; said window unit comprising spaced, parallel glass panels, a continuous spacing member between said glass panels at the periphery thereof and providing a seal therebetween, a continuous rim having a flat portion arranged to seat on one of said glass panels on the surface thereof remote from said spacing member, a continuous channel-shaped clamping member having fixed parallel sides and arranged around the edges of said glass panels and clamping said rim against said one glass panel and said spacing member in sealing relation between said glass panels; said rim having a portion projecting away from said window unit with the outermost edge thereof disposed so as to abut the inwardly extending flange of the adjacent door panel for locating said window unit relative to said door panels when said window unit is assembled with a stove door in which it is to be used.
2. A window unit according to claim 1 wherein one of the fixed parallel sides of said clamping member is seated against said flat portion of said rim and said projecting portion of said rim is U-shaped so as to overlap said clamping member and the innermost portions of said inwardly extending flange on said adjacent door panel.

HERBERT E. MILLS.
